[57] CLAIM

The ornamental design for a combined dispensing box for pills and electric alarm, as shown and described.

DESCRIPTION

FIG. 1 is a top plan view of a combined dispensing box for pills and electric alarm, showing our new design;

FIG. 2 is a right side elevation view thereof, for which the left side is a mirror image;

FIG. 3 is a bottom plan view thereof;

FIG. 4 is a front end elevation view thereof; and

FIG. 5 is a rear end elevation view thereof.
